BY

W. W. Dudley, *his Attorney*

UNITED STATES PATENT OFFICE.

JAMES P. BROWN, OF HILLSBORO, ILLINOIS.

COLLECTION AND DELIVERY MAIL-BOX.

SPECIFICATION forming part of Letters Patent No. 670,553, dated March 26, 1901.

Application filed January 10, 1901. Serial No. 42,770. (No model.)

To all whom it may concern:

Be it known that I, JAMES P. BROWN, a citizen of the United States, residing at Hillsboro, in the county of Montgomery and State 5 of Illinois, have invented certain new and useful Improvements in Collection and Delivery Mail-Boxes; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to mail-boxes designed for use more particularly on rural mail-routes, and has for its object the production of an improved mail collection and delivery box possessing advantages in point 20 of simplicity and durability of construction, added to which the box is weatherproof, is readily opened and closed, and is equipped with signaling devices to indicate whether the box contains mail for collection or delivery.

25 Other advantages appear in the following detailed description of my improved box, in connection with which description attention is called to the accompanying drawings, in 30 which—

Figure 1 is a perspective view of a mail-box embodying my invention, the box being closed and displaying the carrier's signal to indicate mail to be collected. Fig. 2 is a similar 35 view showing the box opened. Fig. 3 is a vertical longitudinal sectional view of the box. Fig. 4 is a section on line 4 4 of Fig. 3.

Referring to the drawings by letter, A denotes the bottom of the box, having at its 40 sides depending flanges a, to which are riveted or otherwise secured the box sides B B, and C designates the top, which is of pitch form and which is preferably integral with the sides. The top, bottom, and sides are 45 lap-jointed to the rear wall D, rendering the box absolutely weatherproof.

The upper portion of the front of the box is closed by a wall E, having side and upper flanges e engaged by folds b on the sides and 50 top B C, and rivets are employed to securely fasten the parts together. The wall E is set back from the front edges of the sides and

top, and the front edge of the bottom terminates in substantially the vertical plane of said wall. The wall E has at its lower side 55 an outwardly-projecting flange e', provided centrally with a hole e².

F denotes the door, which in its closed position fills the opening in the front of the box. The door is recessed, being provided with 60 side flanges f f, and a pintle-rod g is passed through the lower ends of said flanges and the sides to enable the door to be vertically swung. The lower end of the door extends below the bottom, and in the lowered position of the door said end engages the bottom and supports the door in substantially a horizontal position. The side flanges of the door are upturned, as at f', and in the raised position of the door the upturned edges engage 70 the edges of the sides and act as shoulders to limit the inward movement of the door and also to render the box weatherproof around the door. At the upper end of the door is an outwardly-extending flange f², having a hole 75 f³, which when the door is raised registers with the hole e² in the flange e'. h is a padlock, the shackle of which is passed through the holes e² f³ to lock the door. The outer edge of the door-flange f² is downwardly 80 turned, as at f⁴, to give stiffness and also to provide a finger-hold to facilitate the opening of the door.

I denotes what I term the "carrier's signal." It consists of an arm pivoted by a rivet 85 i to the inner side of the door, and at one end the arm is bent inwardly, as at i', to be readily moved and to frictionally hold the arm in its positions, while its other end is of sufficient length to extend when the arm is moved 90 to display position well below the lower edge of the door to be readily seen by the carrier from the road. The carrier's signal is moved into display position by the person depositing the mail for collection, and this can be 95 accomplished only when the door is in open position.

The patron's signal (shown at J) consists of an arm pivoted at its lower end by a rivet j to the side of the box, preferably at its upper 100 front corner. When mail is deposited by the carrier for delivery, he raises the arm J to vertical position, where it is held by a clip j² on the box side, and in such position the

arm extends above the box sufficiently to be plainly seen from a reasonable distance. Both signal-arms are folded at their edges to give stiffness.

5 The box is preferably constructed throughout of non-oxidizable sheet metal and is devoid of curves and therefore readily constructed with ordinary tools. The top and sides of the box are formed from a single sheet of metal, and all other parts are constructed equally simple, thus enabling the box to be built at a low cost. The flanging of the parts of the box secures stiffness, and the use of lap-joints and rivets, as well as the 10 other provisions hereinbefore specified, renders the box perfectly weatherproof. The door is hinged to swing downwardly and is held when lowered in line with the bottom of the box, thereby facilitating the insertion and 15 withdrawal of the mail-matter. The provision of the holes in the door and front wall flanges to receive the padlock-shackle adds further to the simplicity, effectiveness, and security of the construction and dispenses 20 with the use of separate tongues, staples, or 25 their equivalent for the purpose.

It will be understood that in practice the box is secured to a post or other upright at the proper height to be accessible to a person 30 standing on the ground or seated in a vehicle.

I claim as my invention—

1. A mail-box having a recessed front wall above the box-opening said wall having at its lower side an outwardly-projecting flange provided with a hole to receive the shackle of a padlock, and a door hinged to swing vertically and extended at its lower end below the 35 bottom of the box whereby it is supported in its lowered position by said bottom, said door 40 also having at its upper end an outwardly-

projecting flange provided with a depending portion and with a shackle-hole registering with the hole in the front-wall flange when the door is in closing position.

2. A mail-box having a recessed bottom and 45 a recessed front wall above the box-opening having an outwardly-projecting flange, and a door hinged above its lower end to swing vertically and provided at its upper end with an outwardly-extending flange having a depending portion and with side flanges having upturned edges adapted when the door is closed to shoulder against the edges of the sides of the box-body.

3. A mail-box having a peaked top and a 55 recessed front wall above the box-opening said wall having at its lower side an outwardly-projecting flange, and a door hinged to swing downwardly and extended at its lower end below the bottom of the box whereby it is supported in its lowered position by said bottom, said door also having at its upper end an outwardly-projecting flange provided with a downturned portion and having side flanges upturned at their edges to embrace the edges of the sides of the box-body 60 when the door is raised.

4. In combination with the body of a mail-box, a swinging door therefor, and a signal-arm pivoted to the inner side of the door and 70 adapted to be swung to bring one end below the door into display position the other end of the arm being inturned to frictionally hold the arm in its positions.

In testimony whereof I affix my signature 75 in presence of two witnesses.

JAMES P. BROWN.
